UNITED STATES PATENT OFFICE.

FRANK YOUNG, OF KNIGHT'S LANDING, CALIFORNIA.

DESIGN FOR A CUFF.

SPECIFICATION forming part of Design No. 27,026, dated May 4, 1897.

Application filed March 22, 1897. Serial No. 628,786. Term of patent 7 years.

To all whom it may concern:

Be it known that I, FRANK YOUNG, a citizen of the United States, residing at Knight's Landing, in the county of Yolo and State of California, have invented and produced a certain new and original Design for Cuffs; and I do declare the following to be a full, clear, and exact description of the invention, such as will enable others skilled in the art to which it appertains to make and use the same.

My invention relates to a new and original design for a cuff; and it consists of a cuff of the outline and configuration shown in the accompanying drawings, in which—

Figure 1 is a view of the cuff-blank, and Fig. 2 a view of the cuff when folded to be used.

The leading feature of my design is a cuff of substantially rectangular form, one of the

upper corners of which is inclined downward and outward, as shown at A, and formed with a crease B to produce the triangular flap C, below the base of which is a V-shaped slot D. The other upper corner is likewise formed, with the exception that the base of the triangular slot D is rounded, as shown at E. At the ends of the cuffs are provided slits F.

Having thus described my design, what I claim, and desire to secure by Letters Patent of the United States, is—

The design for a cuff, substantially as herein described and shown.

In testimony whereof I hereunto affix my signature in presence of two witnesses.

FRANK YOUNG.
